Patented May 31, 1927.

1,630,285

UNITED STATES PATENT OFFICE.

JOE OLGIERD ZDANOWICH, OF LONDON, ENGLAND.

MANUFACTURE OF ARTIFICIAL SILK OR THE LIKE.

No Drawing. Application filed August 12, 1926, Serial No. 128,916, and in Great Britain May 6, 1925.

This invention primarily relates to the drying of artificial silk and the like prepared from acetylated solutions of cellulose acetates but it is of wider application as will be indicated below.

The invention is of particular use in connection with the production of artificial silk according to the processes of my British Specifications Nos. 139,232, 190,732, 196,641, 10 200,186, 203,599, 227,134, 244,148 and 9,397 of 1925 in which acetylated cellulose acetate solutions are directly extruded into a coagulating bath for the formation of transparent flexible tenacious films or threads without 15 first precipitating cellulose acetate and then dissolving the precipitate.

I have found that there is considerable difficulty in obtaining the best results in the manufacture of such threads or filaments 20 apparently because the process is hardly the drying of a formed wet thread or film but rather the conversion of a chemical compound or mixture into a mechanically strong thread or film.

To enable this conversion to be effected successfully I have found that the thread must be permitted to contract on formation into a dry thread to a very considerable extent indeed. It is best expressed by stating 30 that the thread or film shall be allowed to contract freely.

Winding spools made to permit reduction of tension in drying materials including artificial silk, artificial horsehair and yarns 35 have already been proposed and these if made of suitable materials, sizes and dimensions may be employed according to the present invention so long as they are arranged to permit free shrinkage of the acetylation 40 mixture or the like on its formation into a dry thread or film.

The invention consists in a method of forming dry artificial silk threads, films or the like according to which a freshly formed 45 silk thread is permitted during the drying operation to contract substantially freely and is dried on a resilient bobbin or spool in such a manner that undue tension is avoided and the tension due to the initial 50 winding operation increases slowly and continuously during the drying operation.

In carrying the invention into effect in one form by way of example a spool is constructed from a sheet of perforated aluminum about 4 to 6 inches wide and about 6 55 to 7 inches long. This is rolled into the

shape of a spiral. A number of similar spools are thus made and placed on spindles, the outer diameter of the spools being preferably as closely as possible the same. On 60 the spools freshly coagulated artificial silk is wound. When the appropriate length of thread has been wound on to the spool the latter is removed from the spindle and dried, for example in an oven at the appropriate 65 temperature. During drying if the thread shrinks the formation of the spool prevents undue stresses in the fibre.

According to a modification in place of forming the spool as a spiral it may be 70 formed as a gapped cylinder. During winding of the thread on to the cylinder the gap is preferably closed by a block or wedge, this being removed before drying takes 75 place.

In place of either of the above forms any other method of spring-supporting the thread in such a manner that undue stresses are not set up during drying may be employed, for instance springs such as clock 80 springs can be used inside a light split or spiral tube or band.

The spools if made in the form of a spiral or cylinder or in any other manner may be 85 formed from metal or other material of uniform or non-uniform thickness.

The spools may be made of any kind of metal, for example of bronze or aluminium, or of any other material possessing appropriate resilience, for example celluloid.

The spools may be made of perforated metal or other material or of imperforate substances.

The dimensions of the spools both in length and width may be varied as required.

The spools when on spindles and while the thread is being wound may be kept in their form and diameter by two rings or bands or plates fixed on both ends of the spool inside or outside or both, these being removed during the drying process. Spools so prepared can be fixed on spindles in any appropriate and convenient manner, preferably in an easily detachable form.

The invention may be applied in the manufacture of artificial silk in the form of threads, ribbons or other films, filaments or the like by the processes of the Zdanowich British specifications numbered as above or artificial silk or the like prepared by any 100 other process where a contraction is likely to occur and tension is to be avoided, for ex-

ample the viscose process, other cellulose acetate processes, whether dry spinning be employed or not, cuprammonium processes and collodion silk processes.

It is found that by the present invention, excellent results are obtained even with the finest counts of silks, such as 2½ to 3 denier per separate strand.

Having now described my invention, what I claim as new and desire to secure by Letters Patent is:—

1. The process which consists in the extrusion of a directly spinnable acetylated solution of cellulose acetate into a coagulating

bath, winding of the forming filament under substantially no tension and completing the formation of the filament with spontaneous slight increase of tension.

2. The process which consists in the extrusion of a directly spinnable acetylated solution of cellulose acetate into a coagulating bath, winding of the forming filament on a freely contractible spool under substantially no tension and drying the so wound filament in place on the spool.

In testimony whereof I have signed my name to this specification.

JOE OLGIERD ZDANOWICH.
